UNITED STATES PATENT OFFICE.

PAUL E. KLOPSTEG, OF CHICAGO, ILLINOIS, ASSIGNOR TO CENTRAL SCIENTIFIC COMPANY, OF CHICAGO, ILLINOIS, A CORPORATION OF ILLINOIS.

EDUCATIONAL APPARATUS.

Application filed May 6, 1926. Serial No. 107,213.

The principal object of this invention is to produce apparatus for measuring the velocity of a projectile, and for illustrating Newton's second law of motion, and the 5 conservation of momentum by means so simple that beginners can successfully use it and yet involving principles so fundamental as to intrigue the interests of advanced investigators.

More specifically, it is the object of the invention to combine a ballistic pendulum with a projectile impeller and a stop mechanism that will permit the investigator to first subject the pendulum to the action of the projectile and hold it in its biased or deflected position while the proper measurements are made, and later permit the projectile to be thrown free of the pendulum to trace its trajectory to a selected level whereby the 20 determinations can be checked accurately and scientifically.

Further objects and advantages of the invention will become apparent as the disclosure proceeds and the description is read in connection with the accompanying drawings illustrating a selected embodiment of the invention, and in which

Fig. 1 is a side elevation of the preferred form of apparatus, the propeller mechanism 30 being shown in vertical section and the bob being shown in normal position in solid lines and in deflected position in dotted lines;

Fig. 2 is an enlarged section through the bob taken in the plane of the paper in Fig. 1;

Fig. 3 is a vertical section of a fragment taken on the line 3—3 of Fig. 1;

Fig. 4 is a vertical section of a fragment taken on the line 4—4 of Fig. 1, and

Fig. 5 is a side elevation similar to Fig. 1, 40 indicating the use of apparatus in determining the time of flight of a projectile.

The preferred form of apparatus here illustrated is grouped upon a heavy cast iron base 10, having legs 11, equipped with rubber feet 12, to protect the top of the table 13 (Fig. 5) or other furniture upon which the apparatus may be placed.

Adjacent to one side and between the ends of the base an upright mast 14 is erected, the 50 upper end of which is equipped with a boom or head 15 consisting of a hollow boss 16 (Fig. 3) receiving the mast and a laterally

projecting arm 17 having spaced downwardly projecting lugs 18 equipped with adjustable pivot bearings 19 and 20.

55

A massive bob 21 is fixed to the lower end of a light rod 22 which has an enlargement or cross piece 23 (Fig. 3) at its upper end provided with conical sockets 24 to receive and cooperate with the conical points 25 60 from the pivot bearings 19 and 20.

The bob 21 is provided with a substantially cylindrical bore 26 (Fig. 2) opening to the right in the position of the apparatus here shown. Adjacent to the left side of the bob 65 this bore is enlarged as indicated at 27 to receive the outer edge of a cushion 28 formed of ordinary steam packing, or other composition of that character. Beyond the steam packing the bore is reduced to a finger hole 70 29 to admit a finger to eject the ball 30. The ball is held in the bore 26 by a spring 31 secured to the bob at 32, bending downwardly and then upwardly, as indicated at 33, whereby it will readily admit the ball 75 and then retain it in position to continue the center of gravity of the suspended mass in line with the axis of the rod 22.

On the front side of the bob is an indicator 34 adjustably mounted in a slot by the 80 screw 35 and having a point 36 to be set opposite to the center of gravity of the suspended mass.

Adjacent to the right of the base 10 is a propeller frame 37 having a flanged foot 38 85 secured to the base 10 and projecting at 39 to the right beyond the base 10, where it terminates in a downwardly inclined pistol-grip 40. On the upper side of the frame 37 at each end are spaced bosses 41 and 42 90 bored in alignment with the axis of the bore 26 of the bob 21. A propelling rod 43 is mounted to move on these bores and is reduced at 44 to enter a hole 45 in the ball 30 which serves as a projectile in the use of the 95 apparatus. The bore of the boss 42 is larger than the rod and receives a threaded sleeve 46 having a knurled flange 47. Between the sleeve and a collar 48 on the rod a helical spring 49 is coiled. Between the collar 48 and the free end of the rod is a tapered collar 50 terminating in a shoulder 51 adapted to cooperate with the catch 52 on a trigger 53 fulcrumed at 54 on the portion 39 of the

frame 37 and bent downwardly to form the finger arm 55, lying partly in front and partly in a slot in the pistol-grip 40.

On the end of the base 10 opposite to the propelling device and adjacent to one side, a short mast or post 56 is erected out of alignment with the bob 21. A bracket 57 mounted on this post projects laterally and supports a graduated rack 58 in alignment with the bob and adapted to be engaged by a pawl 59, pivoted on the pin 60 extending across the slotted bottom 61 of the bob. The engaging end of the pawl is sharpened, as indicated at 62, and normally sets in position to positively engage the rack. A pin 63 adjacent to the engaging end of the pawl cooperates with the one end of a light positive spring 64 which is wound about the pin 60 and has its opposite end 65 resting against the bob at the base 66 of the slotted portion. The pawl is made very light and the spring is so designed that the engagement of the pawl with the rack, while the pendulum is swinging outwardly, results in a very small amount of resistance, but the pawl quickly and positively engages the rack upon a cessation of outward movement and serves to retain the pendulum at or very close to the limit of its outward movement.

The rack 58 is curved on an arc whose center lies in the axis of the pivot bearings 19 and 20, or the axis about which the pendulum swings. It is graduated and preferably numbered every five notches.

35

Theory.

Measurement of velocity by a ballistic pendulum is based on the principle of conservation of momentum, the latter being defined as the product of mass and velocity of a moving body. The fundamental principle of conservation of momentum is that the momentum of the two masses is the same before and after impact.

Where a projectile is embedded in a pendulum the velocity before impact is zero and after impact according to Newton's second law of motion the common velocity of the pendulum bob and the projectile must be such that the momentum of the combined masses is equal to the momentum of the projectile before impact. This relation may be indicated by the following equation written in two ways:

$$(M+m)V = mv$$

$$v = \frac{(M+m)V}{m} \quad (\text{Eq. 1})$$

where M is the mass of the pendulum, m the mass of the projectile, V the velocity of the pendulum and projectile immediately after impact, v the velocity of the projectile before impact.

The impact causes the pendulum to swing and its center of gravity rise a distance h ,

the kinetic energy at impact must equal the potential energy when the pendulum reaches its highest point. This relation may be written as follows:

$$\frac{1}{2}(M+m)V^2 = (M+m)gh \quad (\text{Eq. 2})$$

$$V = \sqrt{2gh} \quad (\text{Eq. 3})$$

By measuring the height h , weighing the masses M and m and substituting these values in Equation 2, V may be ascertained, then substituting M , m and V in Equation 1 will give the value of v .

The results thus obtained may be checked by data obtained from the flight of the projectile independent of the pendulum. During the time interval t , the projectile will move horizontally through a distance $D = vt$, and during the same interval under the force of gravity it will fall a distance

$$d = \frac{1}{2}gt^2 \quad (\text{Eq. 4})$$

Suppose the projectile, after a flight of t seconds, strikes a horizontal plane at a distance d below its initial position. If the point where it struck and its initial position are known, the horizontal and vertical distances between these points respectively are the values of D and d in Equations 3 and 4. By eliminating t and substituting the measured values of D and d , v is found to be

$$v = \frac{D}{2gd} \quad (\text{Eq. 5})$$

From Equation 4, t , the time of flight can be found.

In the first part of the experiment the ball 30 is placed on the end 44 of the rod 43 and together they are pressed to the right in Fig. 1 until the trigger catches the collar 50. The bob is set at rest in the solid line position in Fig. 1, the trigger is pulled, the projectile is thrown to the left taking the position within the bob shown in Fig. 2 and swinging the bob to the dotted line position shown in Fig. 1. This should be repeated several times and the position of the point of the ball 62 noted. The average will accurately represent the mean height to which the center of gravity of the combined masses has swung. Measuring h' and h^2 and subtracting will give h for use in Equation 3.

For the second part of the experiment swing the bob to the position shown in Fig. 1 and, after setting the propelling device, pull the trigger and permit the ball to trace the trajectory 70 as indicated in Fig. 5. Perform this several times and note the given distance, then measure d and D for use in Equation 5.

The pivot bearing 20 is provided with a knurled head 71 which may be readily screwed in and out of the flange 18 and adjacent to the head it has a shoulder 72 adapted to contact with the flange when the bearings are in proper adjustment. The

pivot bearing 19 is provided with a screw driver slot 73, or the like, by which the initial adjustment can be made. The space between the flanges 18 receives the enlargement 23 with sufficient clearance to permit the latter to be removed when the pivot bearing 19 alone has been withdrawn. This construction enables the student to replace the pendulum after weighing, and set the 10 bearings in proper adjustment by merely screwing up the pivot bearing 20.

The mast 14 is cylindrical and its lower end is received in a cylindrical bore 74 in the base 10. One wall of this bore is 15 equipped with a screw 75 having a conical point 76 and the mast has a conical socket 77 to cooperate with the point. This construction permits the mast to be removed for shipment, or storage, and replaced in proper 20 adjustment by merely inserting it in the socket and setting up the screw 75.

I claim as my invention:

1. In apparatus of the class described, a ballistic pendulum including a massive bob suspended by a light rod having opposed tapered bearing sockets, a support, adjustable pivot bearings carried by the support and cooperating with the tapered bearing sockets, and a stop for limiting the adjustment of one of said pivot bearings.

2. In apparatus of the class described, a ballistic pendulum including a massive bob suspended by a light rod having opposed tapered bearing sockets, a support receiving the rod with clearance, pivot bearings threaded in the support and having tapered ends cooperating with the tapered bearing sockets, and a shoulder on one of said pivot bearings adapted to bear against the support 40 when the bearings are properly adjusted.

3. In apparatus of the class described, the combination of a ballistic pendulum including a massive bob suspended by a light rod, an impeller for directing a projectile against the bob, a bracket out of line with the pendulum, a rack carried by the bracket in line with the pendulum at an angle to its position of rest, and a light spring-pressed pawl carried by the bob in position to engage the 50 rack.

4. In apparatus of the class described, the combination of a ballistic pendulum including a massive bob suspended by a light rod, an impeller for directing a projectile against the bob, a bracket out of line with the pendulum, a graduated rack carried by the bracket in line with the pendulum at an angle to its position of rest and curved on an arc

whose center is the axis of suspension of the pendulum, and a light spring-pressed pawl carried by the bob in position to engage the rack.

5. In apparatus of the class described, the combination of a ballistic pendulum including a bob and a suspending rod, a projectile, and a propeller including a frame having spaced bores aligned with the bob, an impelling rod mounted in the bores and projecting toward the bob to receive the projectile, a spring urging the rod toward the bob, a collar on the rod between the bores, and a trigger mounted on the frame and co-operating with the collar.

6. In apparatus of the class described, the combination of a ballistic pendulum including a bob and a suspending rod, a projectile and a propeller including a frame having spaced bores aligned with the bob, an impelling rod mounted in the bores and projecting toward the bob to receive the projectile, a spring urging the rod toward the bob, means for adjusting the pressure of the spring, and a trigger pivoted on the frame and releasably engaging the rod.

7. In apparatus of the class described, the combination of a base having a socket, a ballistic pendulum including a mast having one end mounted in the socket and provided with a conical recess and a set screw mounted in the base and having a conical point for cooperation with the recess.

8. In apparatus of the class described, a ballistic pendulum including a bob having a bore extending from one side to the opposite side, a cushion secured in the bottom of the bore and a spring projecting into the bore for holding a projectile against the cushion.

9. In apparatus of the class described, the combination of a heavy base having a substantially horizontal top, a ballistic pendulum including a bob suspended by a light rod, a mast mounted at one side of the base between the ends and carrying a support in which the light rod is pivotally mounted on an axis transverse to the base, a propeller mounted at one end of the base and having a propelling rod in alignment with the bob when it is in a position of rest, a support adjacent to the opposite end of the base out of line with the bob, a rack carried by the support in line with the bob and a pawl carried by the bob for engagement with the rack.

In testimony whereof I affix my signature.
PAUL E. KLOPSTEG.
